UNITED STATES PATENT OFFICE.

EDWARD S. RITCHIE, OF BROOKLINE, MASSACHUSETTS.

IMPROVEMENT IN MOWING-MACHINES.

Specification forming part of Letters Patent No. 35,263, dated May 13, 1862.

To all whom it may concern:

Be it known that I, EDWARD S. RITCHIE, a citizen of the United States of America, and now or late a resident of Brookline, in the county of Norfolk and State of Massachusetts, have invented an Improved Machine for Mowing Grass; and I do hereby declare the same to be fully described in the following specification and represented in the accompanying drawings, of which—

Figure 1 is a top and Fig. 2 a rear elevation of it. Fig. 3 is a vertical and transverse section taken through the axis of the driving-pulley of the endless band-knife. Fig. 4 is a horizontal section taken through the axle of the bearing-wheels.

The nature of my invention consists in an endless band-knife, its driving-pulley, a series of teeth, and a continuous or endless carrier or frame, as arranged and applied together substantially in manner and so as to operate substantially as hereinafter specified; also, in an arrangement of a guiding-wheel with the band-knife, whereby the latter, while in rotary motion, is caused to put the former in revolution in a manner to sharpen the cutting-edge of such knife; also, in a peculiar arrangement and application of the band-knife carrier and driving-pulley with respect to the bearing-wheels and their axle; also, in the combination of a clutch and its operative mechanism with the driving bearing-wheel, the knife-operating train of gears, and the knife-carrier, arranged with and applied to the axle of the bearing-wheels substantially as hereinafter specified.

In the drawings, A exhibits a carriage or shaft frame as provided with an axle, B, and two bearing-wheels, C C'. Each of these wheels is so applied to the axle as to be capable of being freely revolved on it and independently of the other wheel. One of them—viz., that marked C—is furnished with an internal gear or range of teeth, a, which engages with a pinion, b, fixed on one end of a shaft, c, which extends across the frame A, and is arranged parallel to the axle B. A gear, d, applied loosely on the shaft c, engages with a gear, e, which runs freely on the axle and engages with a circular range of teeth, f, arranged on the inner or front side of the driving-pulley D of the knife E. The said knife is an endless band or belt of steel, it being ar-

ranged within an elongated frame or carrier, F, shaped as shown in the drawings. The lower part, g, of the carrier is a straight bar, and is provided with a series of teeth, G G G, each of which projects from it laterally and below the part g and over the knife, as shown in Fig. 5, which is a section of one of such teeth, the knife, and the said part g of the carrier. The several teeth G G G are disposed at equal distances apart along the bar g. The endless band-knife extends around the periphery of the pulley D and those of three guide-pulleys, h i k, that part of the carrier which is between the pulleys h and k being furnished with a groove or socket, l, for receiving the knife and holding it in place with respect to the carrier. The carrier and the knife-driving pulley are so arranged with respect to the wheels C C' and axle B as not only to cause the pulley D and a part of the carrier to be between the two wheels, but so that one of them—viz., the wheel C—may project through the carrier, as shown in the drawings. The carrier is connected with the axle by means of two arms, m m, which extend from it and embrace and turn freely on the said axle. Furthermore, the knife is pressed in contact with the driving-pulley D by means of an elastic roller, H, arranged in the carrier, as shown in Figs. 1 and 2. A cylindrical grindstone, I, is also supported by and within the carrier, and has its lower side inclined to the knife, and so arranged with respect to it that the cutting-edge of the knife shall extend across the stone in a chord of an arc of the periphery of such side. In consequence of such an arrangement of the grinder I with respect to the knife, the latter, while in motion lengthwise, will rotate the grinder, which by its circular movements will at the same time be caused to grind down or sharpen the cutting-edge of the knife. A clutch, K, is placed on the shaft c, slides freely thereon, and is for the purpose of so connecting the guard d with the shaft c as to cause it to be revolved by and with such shaft. This clutch is operated by a bent lever, L, whose longer arm is connected with one of the arms m by means of a rod, M, which is jointed to the said lever L and arm m.

From the above it will be seen that the knife and its carrier can be turned laterally about the axle B, and from the position shown in

Fig. 1 into that shown in Fig. 6. The consequence is that while the carrier is being so turned the clutch K will be forced out of engagement with the guard d, which, under such circumstances, will be free to revolve on its shaft.

I would remark, in respect to the arm m, which is next to the wheel C, that its hole r for reception of the axle may have a diameter somewhat larger than that part of the axle which is embraced by it, such being to enable the carrier to vibrate a little vertically, in order that it may readily accommodate itself to the variable surface of the ground on which it may rest while the machine may be in operation.

The operation of the machine may be thus described: While it is being drawn forward on the surface of a field of grass to be mowed, the wheel C', through the train of gears and the pulley D, will transmit a revolving motion to the endless band-knife, which, as it is drawn along the bar g, will cut the blades of grass which may be between the teeth G G G and against its cutting-edge. Now, should the bar g be drawn against a stone or any obstacle such as would be likely to impede the machine or injure the cutting-edge of the knife, the carrier, with the knife, will be tilted backward until the obstacle may be passed. Such a tilting movement of the carrier will tend to cause the clutch to be drawn out of engagement with the gear d, which, having taken place, the rotary motion of the knife will be stopped.

Two important advantages result from the clutch mechanism and the particular arrangement and application of the carrier and its

knife relatively to the axle and its wheels—that is to say, by means of such the knife can pass an obstacle and be thrown out of action; and, furthermore, the carrier may be turned into a horizontal position while the machine may be in the act of being moved either to or from a field of grass, in which case both the wheels will revolve without producing any revolving movement of the knife.

I do not claim an endless band-knife of itself; but

What I do claim in the above-described machine as of my invention is as follows—that is to say:

1. The arrangement of the revolving knife consisting of an endless band of spring-steel, its driving-pulley, a series of teeth, and a continuous or endless carrier or frame, substantially in manner and so as to operate as hereinbefore specified.

2. The arrangement of the grinding-wheel relatively to the endless band-knife.

3. Arranging the band-knife carrier and driving-pulley relatively to the axle and the wheels thereof, as described, and applying the carrier to the axle by means of arms or equivalent devices, so that the carrier may be tilted or moved relatively to the wheels and axle, as specified.

4. The combination of the clutch and its operative mechanism, substantially as described, with the driving-wheel, the train of gears, and the knife-carrier, arranged and applied together as set forth.

E. S. RITCHIE.
